STERILIZING PROCESS

Adiel Y. Dodge, South Bend, Ind.

Application July 13, 1932, Serial No. 622,232

4 Claims. (Cl. 99—219)

My invention relates to a process of sterilization and more particularly to a process of sterilizing liquids or other fluids mechanically.

It has been found that germs or bacteria can be killed or at least rendered inactive by varying the pressure thereon, as by applying a high pressure thereto and then releasing the pressure. This principle has been utilized to some extent but as heretofore practiced has been relatively expensive due to the large amount of energy required to carry it out successfully. It is accordingly one of the objects of the present invention to provide a process of sterilization which does not require the expenditure of a large amount of energy.

Another object of the invention is to provide a continuous sterilization process.

The process may be carried out by confining a body of fluid or liquid to be treated in a cylinder and forcing a piston or plunger into the cylinder to apply a high pressure to the fluid. While the fluid is still confined, pressure upon the plunger may be released whereupon any energy imparted to the fluid in the form of work done upon it during compression will be returned to the plunger and may be stored in a flywheel pending the next pressure stroke of the piston or may be utilized in any other desired manner. In this way substantially all of the energy imparted to the fluid is recovered therefrom.

In order to regulate the pressure to which the fluid is subjected, it is preferably confined in a cylinder which is connected to a spring pressed plunger adapted to yield when the fluid reaches a predetermined pressure. In this way any energy absorbed by the spring during the pressure stroke will be returned to the plunger during the expansion stroke and an accurate regulation of the pressure will be obtained without the loss of any appreciable amount of energy.

Fluid to be treated is preferably supplied to the cylinder under pressure and is controlled by inlet and exhaust valves on the cylinder. These valves remain closed to confine the fluid in the cylinder during substantially the entire pressure and retractile strokes of the plunger and are opened simultaneously upon completion of each operating cycle so that a fresh charge of untreated fluid may force the treated charge from the cylinder. If desired the valves may be timed to produce a pressure lower than the feed pressure at the end of the retractile stroke.

A further feature relates to supplying to a liquid to be treated, a gaseous chemical reagent such as

CO₂ so that it may act on the liquid while it is under pressure.

Other objects and advantages will be apparent from the following detailed description and from the accompanying drawing illustrating a machine for carrying out the novel process and in which:

Fig. 1 is a diagrammatic elevation in section of one form of novel apparatus for treating fluids;

Fig. 2 is a diagram showing one form of valve actuating means for the apparatus shown in Fig. 1; and

Fig. 3 is a diagram of the timing of the cycle of operations.

In general, germs and bacteria can be brought to an inactive state by subjecting the media in which they exist to a very high pressure. In some cases, the sterilization by pressure is rendered more effective by the simultaneous use of an electric current passed through the fluid, or by introducing into the fluid to be compressed a gaseous chemical reagent such as CO₂ gas.

When dealing with liquids and semi-liquids, the fluids may be brought to a high state of compression comparatively suddenly by a high pressure pump. The highly compressed fluid may be allowed to escape through a very narrow slit or valve opening at very high velocities, thus allowing the static pressure to drop rapidly. One way of accomplishing this is by a spring closed valve. The rapid velocity change, and the rapid pressure change both have their good effect toward deenergizing the bacteria and the germs.

This method, however, as heretofore practiced is very extravagant of energy, since the potential energy is converted into dynamic energy and lost. Therefore, I propose that the fluid be subjected to a high pressure against a yielding member such as a spring loaded piston as shown in Fig. 1. Upon the return stroke of the compressor the spring or yielding member will return the energy stored in it to the compression piston during the outstroke of the piston. The energy stored in the fluid during the in-stroke of the compressor piston (all fluids are slightly compressible) will also be returned on the out-stroke of the compressor piston to the fly wheel of the power source. By this method very much less energy is lost.

In order that the compression chamber may be filled, I have worked out a cycle wherein the compression chamber is filled by a pump while the compression piston is near its out position and on its way inward. When the chamber is full the valves close and the compression plunger enters and compresses the fluid and the main spring. During the out-stroke the fluid and the

spring return most of the power to the source. When the compression piston is back the valves are opened and the supply pump pushes the treated fluid out and fills the chamber with a new charge to be treated. To insure complete treatment, the new charge may be a little less than the actual capacity of the compression chamber, thus having an overlap, i. e., some fluid is treated twice.

Referring to the drawing in detail, the construction illustrated in Fig. 1 is a single cylinder compressor but can be constructed to be a multiple cylinder compressor. The compression chamber 5 may be a straight bore in which plunger 6 is caused to reciprocate by any suitable power means through a crank or an eccentric 7. The eccentric may be surrounded by a ball bearing to reduce friction. A box yoke 8 is provided as part of the mechanism used to convert rotary motion into reciprocating motion and is attached to the plunger 6. As a guide for the box yoke 8, rod 9 is provided but other forms of guide might well be used. Part 10 is an auxiliary plunger closely fitting the bore of the compression chamber 5 but free to reciprocate therein. Spring 11 normally holds the auxiliary plunger 10 into the compression chamber 5. The spring 11 abuts any suitable rigidly fixed part 12 which remains stationary with the body 13 of the compression chamber.

The compression chamber 5 is provided with an intake port 14 and an exhaust port 15. These ports are provided with suitable valves 16 and 17 so that communication to and from the compression chamber may be opened and closed.

Part 35 shows a portion of the intake pipe provided with an auxiliary injection nozzle 37 and pipe 36. This pipe and nozzle are for the purpose of injecting into the fluid a gaseous chemical reagent, such as CO₂ gas, air or the like which have been found to be very helpful in sterilizing fluids by compression. This gas injection feature may be omitted entirely in some cases and in others its use is optional even though the parts are retained.

Part 38 is a terminal connection for an electric wire 39, electric wire 42 being the other wire necessary for a circuit. Wire 42 feeds through terminal 44 into electrode 43. Electrode 43 is surrounded with insulation material 40 as is terminal 44 surrounded with insulation material 41. In this way auxiliary plunger 10 contains an electrode within itself. By means of this electrode and the wire 39 fastened to the cylinder casting a current of electricity may be sent through the fluid in chamber 5. This current may pass continuously through the fluid found in chamber 5 or it may be interrupted and caused to pass only at the desired interval. Thus the fluid may be treated with gas and electricity in addition to alternate compression and expansion.

Fig. 3 is diagram showing the timing. Axis X-Y represents the axis along which the piston 6 moves. The circular path of the crank pin or eccentric is divided into the periods A, B, C and D. During period A chamber 5 is being filled and both valves are open; during period B fluid in chamber 5 is being compressed and both valves are closed; during period C piston 6 is moving out and recoil from spring 11 and the fluid is being transferred back to power source and both valves are closed; and, during period D piston 6 is moving out and creating a sub-atmospheric pressure and both valves are closed.

Interval A is used to empty and fill the com-

pression chamber through the ports 15 and 14 by opening the valves 16 and 17. Fluid is forced into the compression chamber through valve 17 by some suitable pressure means, such as a supply pump or a circulating pump (not shown). The incoming fluid to be treated pushes the fluid which has been treated from chamber 5 out through valve 16.

The valves are timed to be mechanically opened during the interval A when the plunger 6 is near its outer extremity. The flow is regulated by a metering valve or the like so that during the interval A of valve opening just sufficient fluid, to be treated, enters the chamber 5 to nearly fill it and force out most of the fluid which has just been treated. By regulating this flow so that only 80% to 90% of the quantity needed to refill chamber 5 is forced in, there is only a like amount forced out, thus leaving a remaining quantity of treated fluid in the chamber 5. This overlap insures a thorough treatment of all the fluid passing through my process. Valves 16 and 17 are opened and closed at the same time by any suitable mechanical means such as shown in Fig. 2. Arms 30 and 31 are attached to valves 16 and 17. The arms are connected by suitable linkage to the power shaft and caused to rock at the correct intervals to open the valves 16 and 17 when the plunger 6 is near its outer extremity. With this arrangement when a feed pump is used to fill the compression chamber the displacement of the compression plunger need be only a small portion of the volume of the chamber, thus saving energy over and above a practice of using a high pressure plunger to displace substantially all of the volume of its chamber.

In operation, fluid is forced into the compression chamber, during interval A the valves are closed, the plunger further enters during interval B and compresses the fluid (to a degree necessary to accomplish the desired results, which may be as high as 10,000 lbs. per sq. in. or more, in some cases). The spring 11 yields to the load and absorbs the force of the compression stroke B, but returns the force during the out-stroke C of plunger 6 at which time the spring 11 forces plunger 10 into the chamber 5, thus forcing plunger 6 out and returning the force to the driving shaft 19 through cam 1, etc. During this time any energy absorbed by the fluid during the compression stroke will also be returned to the plunger 6. During interval D piston 6 is drawn further out creating a sub-atmospheric pressure in the fluid and following this interval the valves are opened. During interval A more fluid is forced in through valve 17 thus pushing out most of the fluid which has been treated, through valve 16. The valves close when a volume of fluid, somewhat less in quantity than the volume of chamber 5, has passed valve 17. The plunger 6 enters and the cycle is repeated again and again with or without electrifying the fluid as the needs warrant. Gas may be introduced through nozzle 37 when needed to deenergize "spores".

By using a three or more cylinder compressor the valves and plungers may be timed so that practically a continuous flow of fluid such as water, milk, fruit juices or the like can be treated with pressure which quickly alternates from low to high pressure and back to lower pressure. In some cases, it may be desirable to treat the fluid with a repeated compression stroke. This can be accomplished by timing the valve opening mechanism so that it opens on every second or third

stroke. This is accomplished by introducing a reduction gear (not shown) between drive shaft 19 and the shaft which drives the linkage for moving arms 30 and 31.

5 While I have shown certain simple forms of my invention it is obvious that it may be embodied in other forms covered and defined by the appended claims.

I claim:

10 1. The process of sterilizing fluids which comprises forcing a charge of fluid into a chamber, applying a compressive force to the fluid, relieving the compressive force, reducing the pressure on said fluid to less than atmospheric and forcing a new charge of fluid into the chamber to 10 force out the treated charge.

15 2. The process of sterilizing fluid which comprises forcing a charge of fluid into a chamber, applying a compressive force to the fluid by a compressive member, relieving the pressure on the fluid while maintaining it confined whereby the energy absorbed by the fluid during compression will be returned to the compressive member and forcing a new charge of fluid into the chamber to force out the treated charge.

20 25 3. The process of sterilizing fluid which com-

prises forcing a charge of fluid into a chamber, applying a compressive force to the fluid by means of a compressive member, limiting the pressure on said fluid by absorbing excess pressure in energy absorbing means, relieving the 5 pressure on said fluid while keeping it confined whereby the energy absorbed by the fluid and energy absorbing means during compression will be returned to the compressive member and forcing a new charge of fluid into the chamber to 10 force out the treated charge.

4. The process of sterilizing fluid which comprises forcing a charge of fluid into a chamber, applying a compressive force to the fluid by means of a compressive member, limiting the pressure 15 on said fluid by absorbing excess pressure in energy absorbing means, relieving the pressure on said fluid while keeping it confined whereby the energy absorbed by the fluid and energy absorbing means during compression will be re- 20 turned to the compressive member, reducing the pressure on said fluid to less than atmospheric and forcing a new charge of fluid into the chamber to force out the treated charge.
